(57) **CLAIM**

The ornamental design for a vehicle grille accessory as
shown and described.

DESCRIPTION

FIG. 1 is a front, top, right perspective view of a vehicle grille accessory, showing the claimed design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict a boundary around the de-emphasized elements, which illustrate portions of the vehicle grille accessory which form no part of the claimed design.
